DRILL BIT

Filed June 15, 1944

UNITED STATES PATENT OFFICE

2,457,960

DRILL BIT

William E. Walker, Houston, Tex.

Application June 15, 1944, Serial No. 540,405

3 Claims. (Cl. 255—61)

1

The present invention relates to new and useful improvements in well drill bits and has for its primary object to provide, in the manner as hereinafter set forth, novel means for automatically indicating, while the tool is in operation in the hole, when said tool becomes worn and dull to the extent of requiring replacement.

Another very important object of the invention is to provide a drill bit of the aforementioned character which embodies unique means for releasing in the hole an indicating fluid or medium to be carried to the surface.

Other objects of the invention are to provide a drill bit of the character described which will be comparatively simple in construction, strong, durable, highly efficient and reliable in operation, compact and which may be manufactured at low cost.

All of the foregoing and still further objects and advantages of the invention will become apparent from a study of the following specification, taken in connection with the accompanying drawing, wherein like characters of reference designate corresponding parts throughout the several views, and wherein:

Figure 1 is an elevational view of a drill bit constructed in accordance with the present invention, a portion being broken away in section.

Figure 2 is a vertical sectional view through one of the blades.

Figure 3 is a diagrammatic view of the electric circuit.

Figure 4 is an elevational view, showing a modification.

Figure 5 is a view in horizontal section, taken substantially on the line 5—5 of Figure 4.

Figure 6 is a view in side elevation of one of the blades of the modification.

Figure 7 is a fragmentary view in elevation of another form of the invention with a portion broken away in vertical section.

Referring now to the drawing in detail, it will be seen that reference character 1 designates a holder having mounted thereon a pair of blades 2 having cutting edges 3. The holder 1 has formed therein a plurality of chambers 4. Ducts 5 extend from intermediate portions of the chambers 4 through the holder 1 and terminate in closed ends adjacent the cutting edges 3 of the blades 2.

The chambers 4 are for the reception of electric batteries 6. Also mounted in the chambers 4, outwardly of the batteries 6 are frangible containers 7. A partition 8 divides the containers 7 into a pair of chambers, one of which is filled

2

with a suitable indicating fluid 9 having a distinguishing color, odor, etc. The other chamber is for the reception of an explosive and has mounted therein an electric heating element 10.

5 The elements 10 are electrically connected to the batteries 6 which, in turn, are grounded to the holder 1. Insulated conductor wires 11 are mounted in the ducts 5 and are connected to the elements 10.

10 It is thought that the manner in which the invention as thus far described functions will be readily apparent in a general way from a consideration of the foregoing. Briefly, when the cutting edges 3 of the blades 2 become dull and worn to the point of needing replacement, the insulation is worn from the conductor wires 11 and said wires are thus exposed and grounded.

15 In this manner the electric circuits which include the heating elements 10 are completed and said elements are heated. The elements 10 ignite the explosive which expels the indicating mediums 9 from the chambers 4 into the hole to be carried to the surface.

In the modification illustrated in Figures 4, 5 and 6 of the drawing, a collar 12 is mounted on the usual stem portion 13 of the holder 1. The collar 12 has formed therein wells or chambers 14 similar to the aforesaid chambers 4 for the reception of the batteries 6, the containers 7 and

20 the heating elements 10 therein, etc. Tubular containers 15 of suitable metal are secured vertically by welding or otherwise on either the front or back faces of the blades 2. The tubular containers 15 enclose one end portion of insulated conductor wires 16 having their other ends electrically connected to the elements 10 in the chambers 14.

25 In operation, when the cutting edges of the blades 2 become dull and wear off sufficiently, the adjacent end portions of the tubular containers 15 and the corresponding end portions of the insulation on the conductor wires 16 are also worn off. In this manner the conductor wires 16 are exposed for grounding and completing 30 the electric circuit, thereby heating the elements 10 for igniting the explosives and ejecting the indicating mediums 9 in the containers 14 from the collar 12 to be carried to the surface.

35 In the modification of Figure 7 of the drawing collapsible bellows type containers 17, for the reception of a fluid 18, are mounted in the chambers 14. Exposed tubes 19 are mounted on the front or back faces of the blades 2 and are connected to the containers 17, said tubes comprising closed ends located adjacent the cutting

edges 3 of said blades. Covers 19' are provided for the chambers 14 in this form of the invention. The covers 19' are provided with suitable vents in order that the chambers are internally exposed to all external pressures, thereby making it possible to utilize the reactive spring pressure on the bellows-like containers 17 as the differential force with which to eject the indicating medium. Coiled springs 20 are mounted under tension between the covers 19' and the collapsible containers 17 to give the necessary fluid ejecting pressure on the containers 17 when occasion requires.

In operation of the embodiment of Figure 7 of the drawing, the closed ends of the tubes 19 are worn off when the cutting edges 3 of the blades 2 become sufficiently dull and worn to require replacement. When this occurs the containers 17 are collapsed by the coil springs 20 for ejecting the fluid 18 therefrom through the tubes 19 into the hole to be carried to the surface.

It is believed that the many advantages of a drill bit constructed in accordance with the present invention will be readily understood and although preferred embodiments are as illustrated and described, it is to be understood that further modifications and changes in the details of construction may be resorted to which fall within the scope of the invention as claimed.

What I claim is:

1. In a drill bit including cutting edges, a closed container mounted on said bit and containing an indicating material, there being a communicable passage extending from said container and terminating at a point within said cutting edges, an explosive cooperatively associated with said container, a source of electric current carried by said bit and grounded to the latter, an ignitable element operatively associated with said explosive and electrically connected to said source, and a conductor insulated from said bit extending through said passage and having one end connected to said ignitable element and its other end positioned in the termination point of said passage, whereby wearing away of the cutting edges to an extent such as to remove the insulation from the end of the conductor complementary thereto and bring said conductor into electrical contact with said bit causes the ignitable element to ignite the explosive and upon the ignition of the explosive to open the container and discharge the indicating material into the surrounding hole.

2. In a drill bit including cutting edges, a closed container mounted on said bit and containing an indicating material, there being a communicable passage extending from said container and terminating at a point within said cutting edges, an explosive cooperatively associated with said

container, a source of electric current grounded to said bit and electrically connected to said explosive, and a conductor insulated from said bit extending through said passage and having one end connected to said source and its other end positioned in the termination point of said passage, whereby wearing away of the cutting edges to an extent such as to remove the insulation from the end of the conductor complementary thereto and bring said conductor into electrical contact with said bit causes the ignitable element to ignite the explosive and upon ignition of the explosive to open the container and discharge the indicating material into the surrounding hole.

3. In a drill bit comprising a holder, blades provided with cutting edges mounted on said holder, a plurality of chambers in said holder, each of said chambers having an electric battery and a frangible container containing an indicating material mounted in spaced relation therein, an explosive interposed between said frangible container and said battery and cooperatively associated with said container, said battery being grounded to said holder, an ignitable element operatively associated with said container and electrically connected to said battery, ducts extending from each of said chambers and terminating at a point within the cutting edges of said blades, and conductor wires insulated from said holder extending through each of said ducts, each of said wires having one end thereof connected to said ignitable element and the other end positioned in the termination point of said duct, whereby wearing away of cutting edges to an extent such as to remove the insulation from the ends of the conductor wires complementary thereto and bringing said conductor wires into electrical contact with said holder causes the ignitable element to ignite the explosive and upon ignition of the explosive to open the container and discharge the indicating material into the surrounding hole.

WILLIAM E. WALKER.
